HAIR CURLING DEVICE

Gerhardt J. Machtemes, La Grange, Ill.

Application March 24, 1933, Serial No. 662,535.

6 Claims. (Cl. 132—33)

This invention relates to a new and useful improvement in a hair curling and waving device and has for one of its principal objects the provision of means whereby a number of different kinds 5 of curls may be given on a single curling rod.

Another and further important object of this invention resides in the fact that the heat radiates from the central portion of the combination curling rod through the hair wound thereon.

10 Another important object of this invention is the inclusion of a removable sleeve portion which thus provides a means whereby a strand of hair may be secured to a slot in the end of the curling rod.

15 Another object resides in the fact that when the sleeve is secured to the rod, the rod may be secured to the supporting member near each end by spring clips at any point in its rotation and is not dependent on grooves, notches or the like 20 to hold it in the desired position.

Still another and further important object of this invention resides in the fact that when the sleeve is in position on the rod, a flat marcel-like wave is obtained, but with the sleeve removed 25 spiral waves or ring curls may be given.

Another and still further important object of this invention resides in the fact that the rod may be easily withdrawn from the curled hair.

Another and further important object of this 30 invention is the fact that the device is compact, extremely light and practically indestructible.

Still another and further important object of this invention resides in the fact that the portions of the curling rod contacting the securing members of the support are smooth.

Other and further important objects of this invention will be apparent from the disclosures in the accompanying drawing and from the following specification.

40 The invention, in a preferred form, is illustrated in the drawing, and hereinafter more fully described.

In the drawing:
45 Figure 1 is a side elevation of the hair curling device of this invention, and shows the curling rod and support therefor in their relative operating positions.

Figure 2 is a sectional view of the device taken on the line 2—2 of Figure 1.

50 Figure 3 is a side elevation of the hair curling device of this invention showing the sleeve removed and the curling rod positioned on a modified support.

55 Figure 4 is a top plan view of the modified supporting member.

Figure 5 is a sectional view of the modified supporting member taken on the line 5—5 of Figure 4.

As shown in the drawing:

The reference numeral 10 indicates in a general way the combination curling rod itself which, in the preferred form, is constructed of a restricted central portion 12 having an outer sleeve portion 14 removably secured to one end and an expanded rear portion 16 corresponding in size to the sleeve 14 on the other end. Upon the end 16 is secured 10 a plug 18 having contact points 20 and 22 for making connections with an electric circuit.

The heating element within the curling rod comprises a porcelain core 24 upon which is wound a fine resistance wire to provide a heating element. Surrounding the fine wire is a porcelain sleeve 26 which serves as an insulator between the fine wire and the inner surface of the metal rod 10.

A slot 28 is provided in the outer end of the rod 20 for the purpose of tying or otherwise securing a strand of hair to the rod itself preparatory to the curling operation.

In operation, for giving a flat wave, the curling rod is mounted on a support 30. This support 25 is made up in two portions which are held in operating position by a hinge 32 on one end and a latch 34 on the other end. In cross section, as shown in Figure 2, each portion has an upper segment for holding the curling rod and a lower 30 portion slightly curved to more readily fit the contour of the head, and having therebetween a recessed portion 36 in which is positioned a resilient material 38 for gripping a strand of hair when the support is in operating position.

Secured in any suitable manner to the under side of the bottom portion of the support 30 is a cork member 40 and a felt member 42 to provide protection to the scalp from the heat generated in the curling rod 10.

Secured to one portion of the upper section of the support is a pair of spring members 44 adapted to grip and maintain the curling rod in operative position.

45 A modified support as shown in Figures 3, 4 and 5, may be used in any curling operations where the hair is tied to the rod itself and where it is not necessary or desirable to have a gripping member 38 between the rod 10 and the scalp. 50 However, it will be apparent that the support shown in Figures 1 and 2 may be used if preferred.

In construction, the modified support is made up of a cork or similar member 46 positioned on a felt base 50. In cross section as shown in Fig-

ure 5, the cork member is shown to have a slightly curved upper surface and a flat bottom.

A slot 52 at one end of the support 46 is adapted for receiving the portion of the strand 5 of hair between the curling rod and the scalp.

The operation of the hair curling and waving device of this invention is extremely simple and a variety of different waves may be obtained by either professional or amateur operators. A flat marcel-like wave is accomplished by separating a strand of hair and clamping it in the combination rod support and clamping member. The hair is then wound upon the rod. The rod is then placed under the leaf springs and on the supporting member where it may be rotated upon its longitudinal axis and thus tighten the hair wound thereon. The expanded ends of the curling rod act to keep the outer edges of the flat strand from loosening. The springs maintain the rod in position, keeping the hair taut as the current is turned on and the heat applied.

For a spiral, ring, or twist curl, the sleeve is removed from the rod and the strand of hair is tied with string close to the scalp and to the slotted portion of the rod. The strand is then wound, either flat or twisted, upon the rod and the end of the strand secured, preferably by tying although clamps may be used. Tightening is accomplished by holding the wound strand 30 with one hand and turning the rod on its longitudinal axis. This operation is carried out before the rod is positioned on the rod supporting member. In placing the rod supporting member in use the slotted end thereof is positioned between the tied portion of the strand of hair and the scalp and the enlarged portion of the rod is then pressed into the clip which maintains the parts in parallel relation. Heat is then applied. If desired, a pad may, in either case, be placed 40 over the wound strand to confine the heat.

Positioned on the surface of the support 46 is an upwardly extending spring clamp 54 which provides a means for maintaining the support and the curling rod 10 in their respective positions.

It will be apparent from the foregoing that herein is provided a novel and useful hair curling device which may be universally used. Moreover, because of its unique construction, it can be used by any one not skilled in the art to which it appertains, for giving any one of a variety of 50 curls or waves.

Furthermore, on account of its rugged construction and simplicity of operation, it may be

used in the home and not confined to professional use.

I am aware that many changes may be made, and numerous details of construction varied throughout a wide range without departing from the principles of this invention, and I, therefore, do not purpose limiting the patent granted hereon otherwise than as necessitated by the prior art.

I claim as my invention:

1. In a hair curling and waving device, comprising the combination of an electrically heated curling rod and a rod supporting member, said rod comprising a restricted portion having a threaded end and a smooth expanded portion 15 having an electric contact plug thereon.

2. In a hair curling and waving device, the combination of an electrically heated curling rod and rod supporting member, said rod comprising a restricted central portion and an expanded 20 portion on each end thereof, the periphery of said expanded portion being smooth, an electric contact plug on the rod, and means on the rod supporting member for clamping the rod thereto.

3. In a hair curling and waving device, an electrically heated curling rod, said rod comprising in combination a member having a restricted portion having a threaded end, and a sleeve member removably secured to the threaded end of the restricted portion. 25

4. In a hair curling and waving device, an electrically heated curling rod, said rod comprising the combination of a member having a restricted portion having a threaded end and an expanded portion and a sleeve member removably secured 35 to the threaded end of the restricted portion, the restricted portion having a slotted end.

5. In a hair curling and waving device in combination, an electrically heated curling rod, said rod comprising a restricted portion having a 40 threaded end and an expanded portion, a sleeve member removably secured to the threaded end of the restricted portion, an electric contact plug and a combination rod support and hair clamping member.

6. In a hair curling and waving device in combination, an electrically heated curling rod, said rod comprising a restricted portion having a threaded end and an expanded portion, and a sleeve member removably secured to the threaded 50 end of the restricted portion, the restricted portion having a slotted end, an electric contact plug, and a combination rod support and hair clamping member.

GERHARDT J. MACHTEMES. 55
